UNITED STATES PATENT OFFICE

127,315

DESIGN FOR A PERFUME BOX

Kathryn Black, Seattle, Wash.

Application February 19, 1941, Serial No. 99,101

Term of patent 7 years

To all whom it may concern:

Be it known that I, Kathryn Black, a citizen of the United States, residing at Seattle, in the county of King and State of Washington, have invented a new, original, and ornamental Design for a Perfume Box, of which the following is a specification, reference being had to the accompanying drawing, forming a part thereof.

In said drawing:

Figure 1 is a front elevational view of a perfume box showing my new design, the rear thereof having substantially the same appearance as the front shown.

Figure 2 is a side elevational view, both sides being the same in appearance; and

The shade lines and stippled portions in the several views of the drawing represent contrasting colored areas.

I claim:

The ornamental design for a perfume box, as shown and described.

KATHRYN BLACK.
